CLAIM

The ornamental design for a dustpan as shown and described.

DESCRIPTION

FIG. 1 is a front elevational view of a dustpan showing my new design;

FIG. 2 is a rear elevational view thereof;

FIG. 3 is a left side view thereof;

FIG. 4 is a right side view thereof;

FIG. 5 is a top plan view thereof;

FIG. 6 is a perspective view thereof;

FIG. 7 is another perspective view thereof;

FIG. 8 is an enlarged view of portion 8 shown in FIG. 1;

FIG. 9 is an enlarged view of portion 9 shown in FIG. 2;

FIG. 10 is an enlarged view of portion 10 shown in FIG. 6; and,

FIG. 11 is an enlarged view of portion 11 shown in FIG. 7. The broken lines illustrated boundaries of the enlarged portions and do not form part of the claimed design.

1 Claim, 11 Drawing Sheets
